Attorney in fact.

UNITED STATES PATENT OFFICE.

JAMES C. MOFFITT, OF WYOMING, ILLINOIS.

CAR-COUPING.

SPECIFICATION forming part of Letters Patent No. 240,836, dated May 3, 1881.

Application filed March 3, 1881. (No model.)

To all whom it may concern:

Be it known that I, JAMES COX MOFFITT, of Wyoming, in the county of Stark, in the State of Illinois, have invented an Improved 5 Car-Coupling; and I do hereby declare that the following is a full, clear, and exact description thereof, reference being had to the annexed drawings, making a part of this specification, in which like letters of reference 10 refer to like parts, and in which—

Figure 1 represents a sectional elevation at the dotted line x ; Fig. 2, a sectional elevation at x , but with the hook-finger $H A$ up instead of down; Fig. 3, an end elevation; Fig. 4, a 15 plan; Fig. 5, a plan of the link-holder $J J K$.

$B B T G$ constitute the frame-work of this coupling. The T -shaped bar M is fastened to the sill of the car, and has the different holes $R' R^2 R^3$, that the coupling may be adapted 20 for different heights of cars by the shifting of the bolt R and of the coupling up or down.

The hook-finger $H A$ is pivoted at P to the lever D , and supported in a raised position by the two projections $F F$. The lever D is 25 pinned at P' to the sides $B B$ of the coupling, and at P^2 to the end of the sliding rod C . To the hook-finger $H A$, at the opening O , a cord or chain can be attached, to enable the brakeman to raise the hook-finger $H A$ without having to descend from the top of the car. 30

The link-holder $J J K$ (shown in plan by Fig. 5) is exhibited as holding the link S in Fig. 1, and in Fig. 2 as lying down in the slots made to receive it. The notches $n n$ in the 35 sliding rod C allow the link-holder $J J K$ to be lifted up as high as, but no higher than, the position shown in Fig. 1.

The right-angled slots $E E$ receive the two projections $F F$ when the hook-finger $H A$ is 40 moved forward a little, so that it then has nothing to support it in the position shown in Fig. 2, but it immediately falls.

The method of operating this car-coupling is as follows: When the two cars are to be 45 coupled together, the link-holder $J J K$ of one

coupling is lifted up to the position shown in Fig. 1, the link S pressed back under it, and the hook-finger $H A$ let down to the position of Fig. 1. In the other coupling the hook-finger $H A$ is raised up and back till it is supported by the projections $F F$, as in Fig. 2. As the two cars are now brought together the projecting link S of the one coupling enters coupling No. 2, the end of the link S pushes against the end of the sliding rod C , and, by 50 means of the lever D , moves the hook-finger $H A$ forward till the slots $E E$ coming over the projections $F F$, it is no longer supported, but falls by its own weight. Now, when the cars go to separate from the rebound the link S 55 pulls the hook-finger forward till the projection T' is held under the edge of the cross-bar T . By this means the hook-finger $H A$ is kept from flying up and releasing the link S . A pull back and up at an angle of forty-five degrees brings the hook-finger to the position shown in Fig. 2, thereby liberating the link S 60 and setting the hook-finger $H A$ ready for coupling again.

What I claim as my invention, and for which 70 I desire Letters Patent, is as follows:

1. In a car-coupling, the combination of the hook-finger $H A$, right-angled slots $E E$, lever D , sliding rod C , projections $F F$, and the coupling frame-work $B B G$, as set forth. 75

2. In a car-coupling, the combination of the hook-finger $H A$, lever D , sliding rod C , frame-work $B B G$, and the link-holder $J J K$, as set forth.

3. In a car-coupling, the frame-work $B B G$, 80 in combination with the T -shaped bar M , bolt R , and holes $R' R^2 R^3$, substantially as and for the purpose specified.

In testimony that I claim the foregoing invention I have hereunto set my hand this 17th 85 day of February, 1881.

JAMES COX MOFFITT.
